LINGERIE STRAP POSITIONING CLIP

Adnah A. Nickell and Charles F. Nickell, Glendale, Calif.

Application February 21, 1958, Serial No. 49,744

Term of patent 14 years

(Cl. D17—3)

Fig. 1.

Fig. 2.

Fig. 3.

This application is a continuation-in-part of our application Serial No. D. 38,852, filed November 10, 1955, now abandoned.

We claim:

The ornamental design for a lingerie strap positioning clip, as shown.
